UNITED STATES PATENT OFFICE.

SAMUEL K. DENNIS, OF CHICAGO, ILLINOIS, ASSIGNOR TO THE PLANO MANUFACTURING COMPANY, OF SAME PLACE.

KNOTTER FOR GRAIN-BINDERS.

SPECIFICATION forming part of Letters Patent No. 615,815, dated December 18, 1898.

Application filed April 22, 1898. Serial No. 678,521. (No model.)

To all whom it may concern:

Be it known that I, SAMUEL K. DENNIS, a citizen of the United States, residing at Chicago, in the county of Cook and State of Illinois, have invented certain new and useful Improvements in Knotters for Grain-Binders, of which the following is a specification.

My invention relates to certain improvements in the cord-holders of knotters for grain-binders, and is concerned especially with the upper member of the clamping mechanism which is generally called the "hood."

My invention relates, first, to a construction in which the hood proper is detachably mounted in the framework, instead of being integral therewith, so it can be readily removed and replaced in case of wear with a very slight expense.

It further relates to such a method of mounting the hood as will cause the pressure of the cord tending to separate the clamping members to be transmitted directly to the point of support of the hood, so as to prevent any tendency of the clamping members to bind upon each other.

My invention finally relates to a construction in which a portion of the hood is so shaped that by its co-operation with the other clamping member it prevents any possibility of the cut-off ends of the cord working in between the actual bearing-surfaces of the clamping members, and thereby unduly expanding them, so as to prevent their accurately holding the cord that is being tied.

Referring to the drawings, in which the same letters of reference are used to designate identical parts in all the figures, Figure 1 is a side elevation of a knotter constructed in accordance with my invention and with a portion of the breastplate broken away to disclose the tying-bill and cord-holder, the parts being in the position at which they remain at rest between the actual tying operations. Fig. 2 is a similar view, but with the

breastplate in central longitudinal section and with the tying-bill turned about a quarter of a revolution from the position of Fig. 1 and with the needle advanced to the position it occupies during the actual operation of tying the bundle. Fig. 3 is a section on the line 3 3 of Fig. 1, on an enlarged scale,

showing the cord-holder in elevation. Fig. 4 is a plan view of the cord-holder and tying-bill in the relative positions of Fig. 2. Figs. 5, 6, and 7 are a top plan view, side elevation, and a bottom plan view, respectively, of the hood or upper clamping member of the cord-holder. Figs. 8 and 9 are top plan views and side elevations, respectively, of the tying-bill and cord-holder in the relative positions 55 these parts assume at the time when the knot is almost tied, showing the relation of the two strands of the cord. Figs. 10 and 11 are similar views of the cord-holder in the positions of Figs. 8 and 9, but showing the old form of 60 cord-holder and the relation of the two strands of the cord possible under the old construction. Fig. 12 is a top plan view of the lower cord-holder member or disk without its chilled portion in place. Fig. 13 is a 65 similar view of the cord-holder disk after the chilled portion thereof is cast in its place, and Fig. 14 is a section thereof on the line 14 14 of Fig. 12 with its chilled portion in place.

While my invention is capable of being applied to the various forms of cord-holders, I have shown my invention as applied to the form of cord-holder shown in the patent to Stewart, No. 512,762, January 16, 1894, to which patent reference is made for a fuller 80 disclosure and description of the construction and operation of the parts of the knotter not strictly concerned with my present invention.

In the drawings, A represents the breast-plate, B the binding-arm or needle-arm, and 85 C the knotter-frame, which is mounted on the breastplate. The binding-shaft D, mounted in any suitable way, passes through a tubular bearing at the upper end of the knotter-frame, and the segmental gear-wheel E is 90 fastened to this shaft as usual. The knotting-hook F is of the ordinary bill-hook type and is mounted in the frame C and actuated by the gear-wheel E in the customary manner.

The moving member G of the cord-holder is of the same general shape as that shown in the patent above referred to and is mounted in the same manner. I show this disk G, however, as having the chilled bearing-surface G', which is cast in the opening G", formed in the malleable body of the disk by

the method more completely disclosed in my application for a patent thereon, Serial No. 675,233, filed March 26, 1898. This construction furnishes an extremely hard chilled bearing-surface on this disk at the point where the greatest wear occurs, and thus adds a much greater life to the cord-holder while in no way interfering with the strength and durability of the malleable body portion of the disk and its bearings.

In the old construction, which is shown in the aforesaid patent and also in Figs. 10 and 11 of the present application, the hood H was integral with and formed a part of the knotter-frame C, while in the present construction I make the hood separate from said frame and of the shape shown in detail in Figs. 5, 6, and 7. This hood has the tubular body portion H', which snugly surrounds the stem G³ of the disk G and yet permits it to rotate freely therein. An offset portion H², extending upward at one side of the body portion H', terminates slightly above the upper surface of the body portion H' and forms a shoulder H³, as best seen in Figs. 5 and 6. Above this shoulder H³ is the pintle or bearing lug H⁴, which takes into a properly-shaped socket formed in the under side of the frame C, so as to permit of a slight vertical movement of the hood H, while preventing its rotation with the disk G. As will be seen from Figs. 1, 2, and 9, this pintle H⁴ is substantially in a line between the axes of the cord-holder and of the tying-bill and at a position where it is directly over that portion of the cord-holder where the greatest strain is transmitted to the cord. The location of the bearing at this point serves to transmit the stress of the cord in a line parallel to the axis of the cord-holder and prevents any tendency for the hood to cramp and bind upon the stem G³ of the cord-holder disk, which tendency would be present if the binder were at another position, say one hundred and eighty degrees from the location shown, where the stress from the cord would be transmitted to the bearing-surface at an angle of substantially fifty degrees with the axis of the cord-holder instead of parallel thereto.

By making the hood proper separate from the frame C and giving it a certain amount of play I am enabled to accommodate the cord-holder to the different thicknesses of twine as well as to replace the hood readily and with a slight expense in case it becomes worn through the friction of the cord or otherwise, as is frequently the case. This making of this hood detachable also enables me to construct it of chilled or otherwise hardened metal, which cannot be done if it is integral with the frame C.

The second feature of my invention relates to the employment of the deflecting-wing H⁵ upon the hood. This deflecting-wing is of the shape best shown in Figs. 5, 6, and 7, and extends from where the conical surface of the

cord-holder disk begins down almost to its edge. The curved edge H⁶ thereof is tapered down so as to form a kind of a shearing-plate 70 to operate in connection with the conical surface of the disk G to shear the cut-off ends of the cord. The action of this deflecting-wing H⁵ in preventing any possible clogging of the cord-holder by the cut-off ends of the 75 twine is best shown in Figs. 4 and 8 to 11 inclusive, Figs. 10 and 11 of which represent the possible action of the old construction when a long end of the twine is cut off.

Referring to the position of the parts shown 80 in Fig. 4, in which the tying-bill has made about a quarter of a revolution and the cord-holder is about to begin its rotation, it will be seen that the free end T of the twine, which is subsequently to be cut off against 85 the knife I, is carried by the arm G⁴ around the axis of the cord-holder. When the disk G is revolved through about one hundred and twenty degrees to the position shown in Figs. 8 to 11, if the old construction is employed and the free end T is unusually long there is the possibility of it being carried beneath the needle-strand of the cord and being clamped by said needle-strand upon the conical face of the disk, as shown in Figs. 10 95 and 11. If it becomes clamped in this position during the subsequent revolution of the disk, and especially after the end has been severed by the knife I, it almost invariably becomes carried in between the conical 100 surface of the disk and underneath the quadrant H⁷ of the hood. There is then nothing to dislodge it from this position and it becomes wrapped around the shaft G³ of the cord-holder disk at the termination of the conical 105 surfaces, and thus separates the two clamping members, so that they fail to hold the free end of the cord properly and the knotter fails to tie on account of the slipping which can result. In my improved construction, 110 where the wing H⁵ is employed, it will be seen that the curved edge H⁶ of the wing tends to shear and guide the free end T of the cord off from the cone and down to the position shown in Figs. 8 and 9, where it becomes 115 impossible for the needle-strand of the cord to clamp it upon the cone and to carry it beneath the quadrant H⁷. Even if it should be carried upon the wing H⁵ and be clamped there by the needle-strand there would not 120 be any possibility of its being carried beneath the quadrant H⁷, owing to the fact that the wing H⁵ is stationary.

It will be seen that I have devised certain new and useful improvements in cord-holders, 125 that my invention is capable of some modifications, and that I do not desire to be limited to the exact forms shown and described, only so much as may be necessitated by the prior art.

I claim—

1. In a knotter, the combination of the frame, with the cord-holder disk having its stem revolubly mounted in said frame, the hood mounted upon the stem between the

frame and the disk, connections between the frame and the hood for holding it from rotation with the disk, and means for rotating the disk, substantially as shown and described.

5 2. In a knotter, the combination of the frame C, with the tying-bill F, the cord-holder disk G having its stem G³ revolubly mounted in said frame C, the hood H mounted upon the stem G³ between the frame C and the disk G, connections between the frame C and the hood H for holding it from rotation with the disk, said connections being located substantially in a line between the axes of the tying-bill and cord-holder shafts, and means for rotating the disk and tying-bill, substantially as shown and described.

10 3. In a knotter, the combination of the frame, the tying-bill mounted in said frame, with the cord-holder disk having its stem revolubly mounted in said frame, the hood H mounted upon the stem and between the frame and the disk, connections between the frame and the hood for holding it from rotation with the disk, said connections consisting of a lug located substantially in a line between the axes of the tying-bill and cord-holder shafts and coöperating with a socket in the frame, and means for rotating the disk

15 and tying-bill, substantially as shown and described.

4. In a knotter, the combination of the rotating cord-holder disk having the arm G⁴ substantially as and for the purpose described, with the hood having the deflecting-wing H⁵ 35 coöperating with the operative surface of said disk to shear off the cord ends, substantially as and for the purpose described.

5. In a knotter, the combination of the rotating cord-holder disk having the arm G⁴ 40 substantially as and for the purpose described, with the hood having the wing H⁵ with its beveled edge H⁶ coöperating with the operative surface of said disk to shear off the cord ends, substantially as described.

45 6. In a knotter, the combination of the conical rotating cord-holder disk having the arm G⁴ substantially as and for the purpose described, with the hood having the deflecting-wing H⁵ with its under surface conforming to the conical surface of the disk and its beveled edge H⁶ coöperating with said conical surface to shear off the cord ends, substantially as and for the purpose described.

50 SAMUEL K. DENNIS.
